COMBINED DISPLAY AND STORAGE CASE FOR AN ELECTRIC SHAVER

William J. Rakocy, Clifton, N.J., assignor to Ronson Corporation, Woodbridge, N.J., a corporation of New Jersey

Filed May 15, 1968, Ser. No. 11,951

Term of patent 14 years

Int. Cl. D9—04

U.S. Cl. D9—232

FIG. 2.

FIG. 3.

FIG. 4.

FIG. 5.

FIG. 6.

FIG. 7.

FIG. 1 is a front perspective view of a combined display and storage case for an electric shaver showing my new design.

FIG. 2 is a top view thereof.

FIG. 3 is a bottom view thereof.

FIG. 4 is a front view thereof.

FIG. 5 is a right-side view thereof.

FIG. 6 is a rear view thereof.

FIG. 7 is a left-side view thereof.

FIG. 8 is a front perspective view thereof with the hinged left-hand compartment lid opened.

FIG. 9 is a front perspective view thereof with the hinged left-hand and right-hand compartment lids opened.

I claim:

The ornamental design for a combined display and storage case for an electric shaver, substantially as shown and described.
